ELECTRIC LAMP BASE

George J. Edwards, Painesville, Ohio, assignor to General Electric Company, a corporation of New York
Filed May 31, 1962, Ser. No. 198,957
2 Claims. (Cl. 339—146)

This invention relates generally to electric lamps, and more particularly to bases therefor. Still more particularly, the invention relates to bases of the three-contact type generally employed with incandescent lamps of the three-way type having a major and a minor filament and adapted for use in sockets having a switching arrangement for energizing the filaments individually, or both in multiple, so as to obtain three levels of illumination.

The conventional three-contact base comprises a threaded metal shell having a web of insulating material closing one end and projecting outwardly therefrom and carrying an intermediate flat ring contact concentric with the axis of the shell, and a centrally disposed end or center contact. In some instances, erratic operation of the lamp has been experienced in commercially available sockets as, for example, operation at only one light level or flickering between levels.

Accordingly, it is a principal object of this invention to provide an improved construction of the base which will minimize malfunctioning of the lamp in conventional sockets.

Briefly stated, it was found that some sockets departed radically from the average in critical operating dimensions, preventing reliable operation of the conventional base. A contributing factor is the fact that a contact post in many of the sockets is so constructed that the vertical pressure of the conventional intermediate flat ring contact on the base forces the said contact post inward toward the center contact of the socket. In some sockets this causes the post and center contacts of the socket to come into engagement with each other, resulting in operation of the lamp at the same light level on three switch positions. This effect is overcome by employing a base intermediate ring contact of frusto conical shape to thereby force the contact post of the socket outwardly away from the socket center contact. However, in employing a frusto conical ring having a slope sufficient to readily and effectively force the socket contact post outward, there are occasions when the socket post contact is too short and is located too far outward toward the outer edge of the frusto conical ring contact to be firmly engaged by the said outer edge of the ring contact. In accordance with the invention, reliability of operation is materially increased by employing a base intermediate ring contact of composite form including a frusto conical inner portion and a flat planar outer portion whereby to effect outward wedging action and firm engagement of the frusto conical portion with properly located socket contact posts, and also provide firm engagement of the flat outer portion with socket contact posts which are short and are located toward the outer edge of the base ring contact.

A further, correlative, function of the flat planar portion 18 is to limit the depth of travel of the base into the socket before the ring contact 10 meets the contact post 16, in the case just described. If the depth of travel is not so limited, meeting of the ring 10 and the contact post 16 may not occur before the outer edge of the threaded socket-shell 14 passes beyond the thread available on the lamp base. This results in a need for more hand torque to force the base to the required depth and thereby may make the contact less positive when it occurs. This possibility is increased by the existence of a large number of sockets in which the threaded metal shell portion is distinctly longer than that in the average socket.

2

Further features and advantages of the invention will appear from the following detailed description taken in conjunction with the drawing wherein:

FIG. 1 is an elevation of a three-way incandescent lamp provided with a base in accordance with the invention and fitted in a socket which is shown partly in section;

FIG. 2 is an elevation, in section along the line 2—2 in FIG. 3, of the base on an enlarged scale;

FIG. 3 is a top end or plan view of the base;

FIG. 4 is a fragmentary section of the base on a still further enlarged scale.

Referring to FIG. 1 of the drawing, the lamp illustrated therein comprises a glass bulb 1 containing major and minor filaments 2 and 3. Both filaments 2 and 3 are connected at one end to a common lead wire 4 and at their other ends to respective lead wires 5 and 6. The bulb 1 has attached to its end a base comprising a screw threaded metal shell 7 having one end closed by a web 8 of insulating material such as a thermosetting organic plastic. The web 8 carries an end contact or eyelet 9 and an intermediate ring contact 10 concentric with the axis of the shell 7. The common lead wire 4 extends exteriorly of the bulb through a conventional stem tube 11 and is connected to the base shell 7. The lead wires 5 and 6 are connected to respective end and intermediate contacts 9 and 10 by quantities of solder 21 and 12 (FIG. 4) filling the aperture in the eyelet contact 9 and a threading aperture 12' in ring contact 10.

The socket shown in FIG. 1 is of conventional construction and comprises a metal husk 13 containing a screw threaded shell contact 14, flexible center contact 15 and intermediate post contact 16 which are supported from an insulating block (not shown) which also contains the switch mechanism (also not shown). The shell contact 14 is connected to one terminal of a source of current supply, and the said switch mechanism may be arranged to successively connect the other terminal to, firstly, both the end and intermediate contacts 15 and 16 for high level illumination, secondly, contact 15 alone for medium level illumination, and thirdly, intermediate contact 16 alone for low level illumination, followed by an off position.

In accordance with the invention, the base intermediate ring contact 10 comprises an inner frusto conical portion 17 which is enlarged in a direction away from the end contact 9 and terminates in a flat or planar portion 18 in a plane transverse to the axis of the shell 7. As here illustrated the flat portion 18 of the contact 10 is of square outline with its corners 19 bent under and embedded in the body of the insulating web 8.

Upon screwing the base 7 into the socket shell 14, the socket post contact 16 normally engages the sloping sides of the conical portion 17 of the base ring contact 10, thus forcing the said post 16 outwardly away from the socket center contact 15. This is in contrast to the action of a plain flat base ring contact wherein the vertical pressure on the post contact 16 tends to force it inwardly toward the socket center contact 15 with consequent likelihood of engagement of said contacts 15 and 16 resulting in malfunctioning of the switching operation.

In those cases where the socket contact post 16 is located a distance abnormally outward from the center of the socket, it will nevertheless engage the flat outer portion 18 of the ring contact 10, as shown in FIG. 2. This is so even though the post 16 also be of shorter than normal length whereas, even with the base screwed in tightly as far as possible, the said post may nevertheless fail to engage with a simple frusto conical ring contact even if the conical surface 17 were extended downward to be below the post 16. In order to make sure of a positive wiping, wedging action of the conical surface 17 against the socket

contact post 16, it is desirable that the angle of the taper be at least 20°, preferably about 25°.

As indicated in FIG. 4, the solder globule 12 on the ring contact 10 is preferably finished off level with the contour of the sloping and flat surfaces of the contact, and the solder globule 21 on the center contact is finished flat with its surface at a precise distance relative to the surface of the ring contact 10.

This distance is an important factor in minimizing defective electrical contact at either the ring contact or the center contact when variations in socket dimensions are considered.

As also shown in FIG. 4, that portion of the surface of the insulating plastic web 8 which is located between the inner edge of the ring contact 10 and the center contact 9, is preferably grooved as shown at 20 thereby increasing the length of any surface leakage path between those contacts. In addition, this groove facilitates the molding of the plastic when it is undesirable to extend the frusto conical surface to meet the end contact 9. Unless the frusto conical surface is interrupted before it would meet the end contact 9, it is not possible to simultaneously maintain the desired vertical distance between the end contact surface and the ring contact surface, the desired horizontal or annular width of the frusto conical surface 17, and, at the same time, a 25° angle of taper of this surface.

What I claim as new and desire to secure by Letters Patent of the United States is:

1. An electric lamp base comprising a shell, a web of

insulating material closing one end of said shell, a centrally arranged end contact and an intermediate annular ring contact carried by portions of said web projecting beyond said shell, said ring contact comprising an inner frusto conical portion concentric with the axis of said shell and enlarged in a direction away from said end contact toward said shell and terminating at its larger end in an outer flat portion transverse to said shell axis.

2. An electric lamp base comprising a shell, a web of insulating material closing one end of said shell, a centrally arranged end contact and an intermediate annular ring contact carried by portions of said web projecting beyond said shell, said ring contact comprising an inner frusto conical portion concentric with the axis of said shell and enlarged in a direction away from said end contact toward said shell and terminating at its larger end in an outer flat portion transverse to said shell axis, the surface of that portion of said web located between the proximate edges of said end contact and ring contact being formed with an annular groove therein.
